B. J. Gantner

UNITED STATES PATENT OFFICE

JACK FRANCIS MAHON TAYLOR, OF WILMINGTON, CALIFORNIA, ASSIGNOR TO SHELL DEVELOPMENT COMPANY, OF SAN FRANCISCO, CALIFORNIA, A CORPORATION OF DELAWARE

AUTOMATIC END POINT RECORDER

Application filed October 30, 1928. Serial No. 316,089.

This invention relates to the automatic determination of boiling point temperatures, and especially to the determination of the boiling point of the least volatile component 5 of a mixture of fluids.

It is the object of my invention to provide an instrument which automatically at certain regular intervals, to be fixed as desired, will determine such boiling point, and make a 10 record of such determinations, or if desired, control the purity of the fluids or mixture of fluids tested according to the results obtained by such determination.

More particularly my invention provides 15 for the petroleum refining industry an instrument which automatically at fixed intervals will determine the final boiling point of mixtures of hydrocarbon vapors or liquids, and record the results of such determinations, or 20 control automatically certain conditions under which the mixture tested is produced.

Further objects and advantages of this 25 invention will appear from the following description in which I have set forth the preferred form of my invention. It is to be understood that the appended claims are to be accorded the scope and range of equivalents consistent with the state of the prior art.

Petroleum oils, as is well known, consist 30 of a mixture of different hydrocarbons, whose boiling points often are very close together, so that due to the effect of partial vapor pressures it is difficult to separate the different products or fractions, each containing a number 35 of different hydrocarbons, from each other by distillation, as a small part of the hydrocarbons whose boiling points are higher than the temperature of distillation, usually distill over with the lighter hydrocarbons, 40 while a small part of the lighter material remains in the heavier residue. It is very important that this "overlapping" of the fractions be avoided as much as possible, and that as pure products as possible are obtained, with as short a range of boiling points as possible. The market value of the products is seriously affected by the presence 45 therein of hydrocarbons, lighter or heavier than those which belong in such fraction.

50 For this reason in the distilling of petro-

leum a close control is kept of the range of boiling points of the different products. This is usually done by hourly determining this range in the laboratory of the refinery, by means of tests on samples of the different 55 products being manufactured. If these tests show that the "cut" between the different fractions is not sharp enough, the conditions of heating or condensing or otherwise under which the different fractions are produced, 60 are changed, so as to obtain a closer fractionation.

In order to facilitate this control of the boiling point range of the different products, I have invented the instrument which is described hereunder, and which will automatically determine the final boiling point of any 65 product at certain intervals, for instance every ten or twenty minutes, as desired. This determination may be automatically registered in well known manner, or it can be combined with automatic control of conditions in the distillation apparatus, by means of any of a number of well known devices, or both recording and control can be combined. 70

An apparatus designed for carrying this 75 invention into effect is illustrated more or less diagrammatically in the accompanying drawing which shows by way of example an apparatus adapted for the determination of the final boiling point of a mixture of liquid hydrocarbons belonging to the gasoline fractions, which is tapped from a main line.

This apparatus consists mainly of: cooler 1, dehydrator 2, measuring tube 3, and distilling unit 4. Tube 10, provided with needle valve 11, is a $\frac{1}{8}$ inch tube which taps the main line, not shown, and connects with the cooler 1. This cooler consists of coil 12 immersed in water bath 13. Pipe 14 connects the cooler with the dehydrator 2, in which near the top 21, a gauze filter 22 is provided. A central draw-off line 23 leads to the measuring tube 3; 24 is a drain, 25 a by-pass to drain, and 26 a regulating valve. 31 is an air vent for the measuring tube 3. Siphon 32 connects the measuring tube with the distilling unit 4, the siphon bend reaching upward to the level 33 in the measuring tube. 34 Distilling unit 4 consists of metal flask 41

and electric heater 42, together enclosed in the protective gauze screen 43. In the neck of flask 41 a thermocouple 44 is arranged, connected by wires 45. A vapor-line 46 leads to a condenser and drain, not shown.

In operating my apparatus the hot liquid gasoline is drawn off from the main line through tube 10, the amount of feed being regulated by needle valve 11. The gasoline is cooled in cooler 1, and impurities are removed by filter 22; any water settles out in the bottom of dehydrator 2, and is removed through drain 24 together with any excess gasoline. The dry clean gasoline is drawn off through 23 to the measuring tube 3, in which it accumulates until level 33 is reached. The siphon then comes into action and the contents of measuring tube 3 are removed to distilling flask 41, and there distilled by means of heater 42, the vapors being removed through line 46. Thermocouple 44 reacts on the temperatures in the flask and may be connected to a recording device as a Leeds & Northrup temperature recorder, or to any desired device, for automatic control of the

conditions of heating, condensing, etc. in the plant. The amount of feed and the heating are regulated in such way that the distillation of the charge of the flask will be terminated a little before the gasoline accumulating in the measuring tube reaches level 33, so that the flask will be empty when the siphon comes into action; while one charge is being distilled, the next one is accumulating in the measuring tube, thus forming a liquid seal on the apparatus and preventing the blowing back of vapors from the flask. The time interval between the determination of the "end point" or final boiling point of the fraction tested is preferably regulated by changes in the time required to fill the measuring tube up to level 33 of the predetermined volume of the charge. It could be regulated also by changing the volume of the charge, as for instance by adjusting the height of the siphon bend, or otherwise, but it has been found that this is inadvisable, as only by careful manipulation and constant rate of heating can the end point obtained by the device of my invention be made to conform to that obtained by the usual laboratory method. I prefer therefore to regulate the time interval by adjustment of the time of filling the measuring tube up till 33, by means of regulating valve 26.

By comparison with laboratory tests it has been found that this apparatus works very accurately; the variation is usually not more than one degree F. The chart of the recording device shows clearly the gradual rise in temperature during the distillation; for a few minutes the end point will be registered, after which the cooling of the thermocouple because of lack of vapors is recorded followed

by a sudden drop in temperatures when the new charge is siphoned in the flask.

It has been found that a metal flask, preferably a copper flask can be used instead of the glass flask specified for laboratory tests. An indefinite number of tests can be run without coke or gum being formed in the flask to such extent as to affect the end point. If the mixture to be tested is not liquid, but consists of vapors, cooler 1 will be operated as condenser, so that only liquid will flow through pipe 14 to dehydrator 2. Variables which affect the apparatus have been found to be atmospheric conditions and variation in the voltage of the electric heater, both of which can be easily overcome by those skilled in the art. The vapors from the distillation may, if desired, be returned to the main line.

While I have illustrated one form of apparatus suitable to carry out my invention, other designs may be found adapted to obtain the results of my invention, and I do not intend to limit myself to the particular form & Northrup temperature recorder, or to any of apparatus shown.

It will be understood that this or similar apparatus can be used not only in the petroleum industry, but in all cases where the final boiling point of a mixture of vapors or liquids is of importance; arrangements can be provided without difficulty to have condensation and distillation take place under pressure or vacuum, according to the nature of the material tested, without departing from the principle of my invention.

My invention is also adapted to determine the purity of a certain material as regards the presence of a heavier substance; a change in the final boiling point will immediately indicate the presence of such less volatile impurity. For instance in the production of ether the presence of alcohols can be detected in this way.

I claim, as my invention:

1. In a device of the character described, measuring means and a distilling unit, the measuring means being elevated so as to have a hydrostatic head over the distilling unit, the measuring means being so arranged as to form a liquid seal preventing the back flow of vapors from the distilling unit, and a siphon tube connecting the measuring means and distilling unit automatically discharging the contents of the measuring means into the distilling unit at regulated periodic intervals.

2. In a device of the character described, a measuring means and a distilling unit, a valve controlling the rate of flow of liquid into the measuring means, the measuring means being elevated so as to have a hydrostatic head over the distilling unit, the measuring means being so arranged as to form a liquid seal preventing the back flow of vapors from the distilling unit, and a siphon tube connecting the measuring means and the dis-

tilling unit automatically discharging the contents of the measuring means into the distilling unit at periodic intervals regulated by said valve.

5 3. In a device of the character described the combination of the interconnected system comprising, a cooler, a dehydrator, a measuring chamber and a distilling unit, the measuring chamber being so arranged as to form a
10 liquid seal preventing the back flow of vapors from the distilling unit, and the measuring chamber being elevated above, and having a siphonic connection with the distilling unit adapted to automatically discharge the contents of the measuring chamber into the distilling unit at periodic intervals.

15 4. In a device of the character described the combination of the interconnected system comprising, a cooler, a dehydrator, a measuring chamber and a distilling unit, a valve between the dehydrator and measuring chamber regulating the rate of flow of liquid thereto, the measuring chamber being so arranged as to form a liquid seal preventing the back
20 flow of vapors from the distilling unit, the measuring chamber being elevated above, and having a siphonic connection with the distilling unit adapted to automatically discharge the contents of the measuring chamber into
25 the distilling unit at periodic intervals regulated by said valve.

30 5. In a device of the character described the combination of the interconnected system comprising, a cooler, a dehydrator, a measuring chamber and a distilling unit, a valve between the dehydrator and measuring chamber regulating the rate of flow of liquid thereto, the measuring chamber being so arranged as to form a liquid seal preventing
35 the back flow of vapors from the distilling unit, the measuring chamber being elevated above, and having a siphonic connection with the distilling unit adapted to automatically discharge the contents of the measuring
40 chamber into the distilling unit at periodic intervals regulated by said valve, and means for indicating the temperature in the vapor space of the distilling unit.

45 6. In a distillation system, a distillation apparatus, means for continuously withdrawing a small sample of distillate from the distillation apparatus, a small distillation flask, means for introducing said sample into the distillation flask, means for heating said flask and vaporizing said sample, means for regulating a condition of operation of the distillation apparatus, means effected by the final boiling point of the sample of distillate to automatically control the said regulating
50 means to obtain a substantially constant final boiling point distillate from the distillation apparatus.

In testimony whereof, I have hereunto set my hand.

65 JACK FRANCIS MAHON TAYLOR.
